UNITED STATES PATENT OFFICE

THOMAS R. ATKINS, OF CLIFTONDALE, MASSACHUSETTS

DESIGN FOR A SHOE

Application filed January 11, 1933. Serial No. 46,784. Term of patent 3½ years.

To all whom it may concern:

Be it known that I, THOMAS R. ATKINS, a citizen of the United States, residing at Clifftondale, in the county of Essex and State of Massachusetts, have invented a new, original, and ornamental Design for a Shoe, of which the following is a specification, reference being had to the accompanying drawing, forming part thereof, in which—

Fig. 1 is a view in side elevation and Fig. 2 is a top plan view of a shoe showing my new design.

The essential feature of my design is in the ornamental effect produced by the perforated tip and strip of similar finish arranged alternately with the contrastingly finished vamp and quarter.

I claim:

The ornamental design for a shoe as shown and described.

In testimony whereof, I have signed my name to this specification.

THOMAS R. ATKINS.
